J. D. PEDERSEN.
FIREARM.
APPLICATION FILED DEC. 12, 1919.

1,395,292.

Patented Nov. 1, 1921.

Inventor:

John D. Pedersen,
By his Atty, J. A. Richards.

UNITED STATES PATENT OFFICE.

JOHN D. PEDERSEN, OF JACKSON, WYOMING.

FIREARM.

1,395,292.

Specification of Letters Patent.

Patented Nov. 1, 1921.

Application filed December 12, 1919. Serial No. 344,420.

To all whom it may concern:

Be it known that I, JOHN D. PEDERSEN, a citizen of the United States, residing in Jackson, in the county of Lincoln and State of Wyoming, have invented certain new and useful Improvements in Firearms, of which the following is a specification.

This invention relates more especially to that class of firearms usually designated as 10 small arms, and a principal object of the invention is to furnish an improved firing train mechanism and grip-safety device particularly applicable to auto-loading and automatic pistols.

One class of small arms to which my present improvements are applicable includes the auto-loading pistols having a grip-stock or handle portion of the frame or receiver of the firearm, which is adapted to receive a 20 safety device operable by hand grip or compression.

An improved auto-loading pistol of this kind is described in my Patent No. 1,348,733, dated August 3, 1920, and granted on my co- 25 pending application (renewal) Serial No. 311,689, filed July 17th, 1919. Therefore, for convenience of illustration, I have herein shown my present improvements as arranged and applied to the particular kind of auto- 30 loading pistol shown in the drawings of said patent, to which reference may be had.

The features of my firing train mechanism and grip-safety device are that it is a firing train mechanism and a grip or handle containing safety device arranged to prevent firing of the firearm by locking the firing member or hammer and the trigger sear when the grip-operable or grip-safety portion of my device is in normal or safety position.

Also, where the firearm is provided with a main slide comprising a firing-pin, to prevent discharge of the firearm by locking the main slide of the firearm to prevent effective contact between the firing-pin and the cartridge, so that action of the firing member or hammer on the firing-pin will not explode the cartridge.

Another feature of my invention is that it is a firing train mechanism and grip-safety device so organized as to effect the locking of the main slide of the firearm in forward position by means of a combined slide-detainer and controller which engages a face on the main slide that is rearward of the block-abut- 55 ment face of the frame of the firearm for retarding the breechblock in its rearward ac-

tion. In this manner I secure the advantage of a more rigid form of breechblock than the breechblock shown in said patent, and also secure various other advantageous features 60 as elsewhere herein more particularly indicated or described.

In the accompanying drawings which illustrate an embodiment of my invention,—

Figure 1 is a side-view, partly broken away to show the details, of a pistol provided with my firing train mechanism and grip-safety device, the trigger sear and firing member or hammer being locked in firing position and the main-slide locked against rearward movement by the slide-detainer and controller, the grip-operable or grip-safety member of my invention being in normal or safety position.

Fig. 2 is a view of a pistol provided with my firing train mechanism and grip-safety device, showing the rear end of the main slide of the pistol and the rear of the grip-operable or grip-safety member.

Fig. 3 is a sectional detail rear view, of a pistol provided with my firing train mechanism and grip-safety device, the inclosing end of the main slide of the pistol and the grip-operable or grip-safety member being removed.

Fig. 4 is a fragmentary sectional detail view, on larger scale than Fig. 1, of a pistol provided with my firing train mechanism and grip-safety device, the main slide of the pistol being locked by the slide-detainer and controller, and the trigger sear and firing member or hammer being locked in firing position by the slide-detainer and controller, the grip-operable or grip-safety member being grip-compressed to release the 95 slide-detainer and controller for movement to unlocking position.

Fig. 5 is a sectional detail fragmentary view, on substantially the same scale as Fig. 4, of a pistol provided with my firing train 100 mechanism and grip-safety device, the slide-detainer and controller being in unlocking position, the firing member or hammer in fired position, and the grip-operable or grip-safety member being grip-compressed.

Fig. 6 is a sectional detail plan view, on an enlarged scale, on the line 6—6 of Fig. 1.

Similar reference characters or numerals refer to similar parts throughout the several views.

The firing train mechanism and grip-safety device is herein described and shown

as applied to a pistol provided with a main slide and a breechblock comprising a firing pin. The pistol in the present embodiment of my invention is provided with a main 5 slide C, and with a rigid breechblock E, comprising a firing-pin P, the force of the powder gases being first exerted upon the breechblock E to move it rearwardly and transmitted thereby, without the use of any 10 intervening spring or yielding device, to the main slide C to move the main slide rearwardly. The breechblock E is retarded in its rearward movement by engagement with the frame or receiver B of the pistol, chang- 15 ing position or rising by engagement of the face 5¹ with the face 2¹, during which period there is retardation of the breechblock E relative to the main slide C, as at the face 3¹ and face 5¹, while the main slide moves rear- 20 wardly, and the breechblock then moves rearwardly concurrently with the main slide C, until the main slide has reached its most rearward or retracted position. This change of position is accomplished by means of a 25 face 8^k on the breechblock E which engages a block-lifting actuation face, herein shown as a rib-face 33¹, on the main slide C, and the position of the breechblock E, is thereby changed and the breechblock moved and 30 locked to the main slide to afford concurrent movement of the breechblock E with the main slide C after rearward movement of the breechblock itself has been retarded by said engagement with the frame or re- 35 ceiver of the pistol. The retardation of the breechblock E before mentioned, relative to the main slide C, is caused by the engagement of the face 5¹ with the face 3¹, as the breechblock E is retarded in its rearward 40 movement by engagement with the frame of the pistol as before stated and changes its position.

The firing member or hammer H is pivotally supported on the grip-stock of the 45 pistol and is movable to firing position and to fired position. The firing member H is moved from fired position to firing position or cocked position by engagement of the rear-face 10, of the main slide C of the pistol with the forward face of the firing member or hammer H, as the main slide C is moved rearwardly to its most rearward position; or the firing member or hammer H may be moved to firing position or cocked 50 by a suitable roller arranged on the main slide C to engage the firing member or hammer when the main slide is moved to rearward position, or may be moved to firing position or cocked by any suitable means.

60 The firing member or hammer H is provided with a firing notch or cock-notch 8¹, and with an eccentric cam face 8^k, the grip-stock of the pistol being bored out or otherwise suitably cut away, as at 2¹, to receive 65 the firing member or hammer and the vari-

ous parts of my invention. The sear member S is pivotally supported on the gripstock of the pistol and is provided with a locking shoulder 17^b which is engageable with the cock-notch 8¹ of the firing member or hammer H, and is provided with a face 17^a which is engageable with the eccentric cam face 8^k of the firing member or hammer, and is provided with an arm S¹⁰ and with an end-face 17^d. A spring actuated contactor 11 is arranged on the rear side of the sear member S, having a nose or plunger 12, which engages a face 13, arranged to the rear of the cock-notch 8¹ on the firing member or hammer H to force or move the end-face 17^d of the sear member S downwardly when the firing member or hammer H is moved to fired position, Fig. 5.

The slide-detainer and controller N is slidably movable in a guideway 14, milled out or otherwise provided in the grip-stock of the pistol, but any other suitable means for guiding the slide-detainer and controller in its movement may be employed. The slide-detainer and controller N is engageable at 85 its upper end 14^a with the rear face 10 of the main slide C of the pistol to prevent rearward movement of the main slide, and preferably is of curved form to facilitate the engagement of the end 14^a thereof with the rear-face 10 of the main slide C. The slide-detainer and controller N is provided with a shoulder 14^b having an upper surface 14^c with which the arm S¹⁰ of the sear member S is engageable. A slot 15 in the slide-detainer and controller is arranged to receive the trigger-member F and allows movement or play upwardly and downwardly of the trigger member therein. The slide-detainer and controller N is provided with a bottom-face or bottom-side 14^d, and terminates in an end-face 15'.

The actuator 14^m is supported by a bracket 16 mounted on the grip-stock of the pistol, and comprises a nose-piece or plunger 17 and a spring 18. The bracket 16 is bored out to receive the spring 18 and the nose-piece or plunger 17, the spring 18 being seated in the bracket 16 and abutting the lower end of the nose-piece or plunger, the 110 tendency or pressure of the spring 18 being upward. The upper end of the nose-piece or plunger engages the end-face 15' of the slide-detainer and controller N, the purpose of the actuator 14^m being to push or force 115 the slide-detainer and controller upwardly.

The grip-operable or grip-safety member G comprises a base-portion G' and a connecting rod G², the base-portion G' being attached to the grip-stock of the pistol by a 125 pivot-pin g. The connecting rod G² is pivotally attached, or hinged, at its lower end, as at 19 to the upper end of the base-portion G' of the grip-operable or grip-safety member, and is provided at its upper end with a 130

point and enlargement 20, which engages or is received in a hole 21 in the frame of the pistol, the pointed end being permitted a slight upward and downward play or movement in the hole 21 which movement or play is controlled by the adjacent enlargement of the end of the rod. The grip-operable or grip-safety member G is provided with a locking-prong 7^b which is engageable with the firing member or hammer H, thus permitting movement of the firing member or hammer to fired position. As the firing member or hammer H is moved to fired position by the spring 8^e, the eccentric cam face 70 8^k of the firing member or hammer engages the face 17^a of the sear member S, and thereby moves the arm S¹⁰ of the sear member downwardly, which arm engages the face 14^e of the shoulder 14^p of the slide-detainer and controller N and thereby bears down or moves down the slide-detainer and controller against the compression of the actuator 14^m, and the pistol is discharged, Fig. 5, the slide-detainer and controller already having 75 been released by grip-compression of the grip-operable or grip-safety member G for downward movement, as before stated. Movement of the firing member or hammer H from fired position to firing position 80 15^a engages the eccentric cam face 8^k from the face 17^a of the sear member S and permits movement of the sear member upwardly. Through pressure of the actuator 14^m the slide-detainer and controller N is moved upwardly; and the sear member S is moved upwardly until the locking shoulder 17^b of the sear member is locked or engaged with the cock-notch, 8ⁱ, of the firing member or hammer H, the sear member S being moved 95 20^a to this position by contact or engagement of the contactor 11 with the firing member or hammer H. The slide-detainer and controller N is moved upwardly until the upper end 14^a thereof lies in the path of the main 100 slide C of the pistol and locks the main slide at its rear-face 10 against rearward movement, the slide-detainer and controller being blocked or locked in this locking position by the grip-operable or grip-safety member G 105 25^a as later explained.

In operation: The slide-detainer and controller N being in position for blocking the main slide C from rearward movement, and also locking the sear member S and firing member or hammer H in firing position, and the grip-operable or grip-safety member G being non-grip-compressed and in position 45^a of safety, and thereby blocking or locking the slide-detainer or controller in its locking position, Fig. 1, grip-compression of the grip-operable or grip-safety member G releases the locking prong 7^b thereof from engagement with the bottom-side or bottom-face 14^c of the slide-detainer and controller N, thereby permitting downward movement of the slide-detainer and controller from its locking position, Fig. 4. Pull upon the trigger member F engages the inclined face 26 thereof with the end-face 17^a of the sear member S and moves the said end-face rearwardly and upwardly, the contactor 11 being retracted and the locking shoulder 17^b 50^a being disengaged from the cock-notch 8ⁱ of

the firing member or hammer H, thus permitting movement of the firing member or hammer to fired position. As the firing member or hammer H is moved to fired position by the spring 8^e, the eccentric cam face 70 8^k of the firing member or hammer engages the face 17^a of the sear member S, and thereby moves the arm S¹⁰ of the sear member downwardly, which arm engages the face 14^e of the shoulder 14^p of the slide-detainer and controller N and thereby bears down or moves down the slide-detainer and controller against the compression of the actuator 14^m, and the pistol is discharged, Fig. 5, the slide-detainer and controller already having 75 been released by grip-compression of the grip-operable or grip-safety member G for downward movement, as before stated. Movement of the firing member or hammer H from fired position to firing position 80 15^a engages the eccentric cam face 8^k from the face 17^a of the sear member S and permits movement of the sear member upwardly. Through pressure of the actuator 14^m the slide-detainer and controller N is moved upwardly; and the sear member S is moved upwardly until the locking shoulder 17^b of the sear member is locked or engaged with the cock-notch, 8ⁱ, of the firing member or hammer H, the sear member S being moved 95 20^a to this position by contact or engagement of the contactor 11 with the firing member or hammer H. The slide-detainer and controller N is moved upwardly until the upper end 14^a thereof lies in the path of the main 100 slide C of the pistol and locks the main slide at its rear-face 10 against rearward movement, the slide-detainer and controller being blocked or locked in this locking position by the grip-operable or grip-safety member G 105 25^a as later explained.

An important and efficient feature of my invention is that when the firing member or hammer H and sear member S are locked in firing position by the slide-detainer and controller N engaging the rear-face 10, or equivalent abutment means, while the slide-detainer and controller is blocked or locked in this locking position by the grip-operable or grip-safety member G, if the firing member or hammer should be permitted to move from firing position to fired position through the breaking or wearing away of the cock-notch 8ⁱ or the locking shoulder 17^b, the engagement of the cam face 8^k of the firing member or hammer H with the face 17^a of the sear member S will so retard or slow down the actuation of the firing member or hammer to fired position, as to prevent effective contact between the firing member or hammer and the firing-pin P, the slide-detainer and controller N also preventing rearward movement of the main slide and the firing-pin. Grip-compression of the grip-operable or grip-safety member G being 110 115 120 125 130

1 relieved, movement of the firing member or hammer H from fired position to firing position forces the connecting rod 8^b downwardly against the compression of the spring 8^c, and through engagement of the lower end 5 of the rod 8^b with the cupped plunger 8^c an outwardly thrusting or bearing force is exerted on the grip-operable or grip-safety member G at substantially the point of pivot 10 or hinged attachment of the rod G^b to the base portion G' of the grip-operable or grip-safety member G, which force thrusts or moves the grip-operable member or grip-safety member G rearwardly into non-com- 15 pressed position or position of safety, and brings the locking-fork 7^b thereof into engagement with the bottom-side or bottom-face 14^c of the slide-detainer and controller N, and thereby blocks or locks the slide-detainer and controller in upward or locking 20 position.

Having thus described my invention, I claim:

1. In a firearm, in combination, a frame of 25 said firearm, a main slide movable rearwardly and forwardly on said frame and provided with a rear-face, a firing member movable to firing position and to fired position, sear means engageable with said firing member, detaining and controlling means engageable with said rear-face of the main slide, means for moving said detaining and controlling means in direction to lock said main slide against rearward movement, and 30 lock said sear means and firing member in firing position, means for moving said detaining and controlling means in direction reverse to the first mentioned direction when said firing member is moved to fired position, a grip-compressible member engageable with said detaining and controlling means when in position of safety to block said detaining and controlling means in said locking position, and releasable from said engagement 35 by grip-compression, spring means for moving said firing member to fired position, and trigger means engageable with said sear means to move said sear means, when said grip-compressible member is grip-com- 40 pressed, for releasing said firing member for movement to fired position.

2. In a firearm, in combination, a frame of 45 said firearm, a main slide movable rearwardly and forwardly on said frame and provided with a rear-face, a firing member movable to firing position and to fired position, sear means engageable with said firing member, slid- 50 able detaining and controlling means engageable with said rear-face of the main slide, means for moving said detaining and controlling means in direction to lock said main slide against rearward movement, and lock said sear means and firing member in firing position, means for moving said detaining and controlling means in direction reverse to the first mentioned direction when the firing 55

reverse to the first mentioned direction when said firing member is moved to fired position, a hinged grip-compressible member engageable with said detaining and controlling means when in position of safety to block said detaining and controlling means in said locking position, and releasable from said engagement by grip-compression, spring means for moving said firing member to fired position, and trigger means engageable with said sear means to move said sear means, when said grip-compressible member is grip-compressed, for releasing said firing member for movement to fired position. 70

3. In a firearm, in combination, a frame of 75 said firearm, a main slide movable rearwardly and forwardly on said frame and provided with a rear-face, a breechblock movable with said main slide and comprising a firing-pin, a firing member movable to firing position and to fired position and engageable with said firing-pin, sear means engageable with said firing member, slid- 80 able detaining and controlling means engageable with said rear-face of the main slide, means for moving said detaining and controlling means in direction to lock said main slide against rearward movement, and lock said sear means and firing member in firing position, means for moving said detaining and controlling means in direction reverse to the first mentioned direction when said firing member is moved to fired position, a grip-compressible member engageable with 85 said detaining and controlling means when in position of safety to block said detaining and controlling means in said locking position, and releasable from said engagement by grip-compression, spring means for moving said firing member to fired position, and trigger means engageable with said sear means to move said sear means, when said grip-compressible member is grip-compressed, for releasing said firing member for movement to fired position. 90

4. In a firearm, in combination, a frame of 95 said firearm, a main slide movable rearwardly and forwardly on said frame and provided with a rear-face, a firing member movable to firing position and to fired position, sear means engageable with said firing member, means for moving said firing member to fired position, slid- 100 able detaining and controlling means engageable with said rear-face of the main slide, means for moving said detaining and controlling means in direction for locking said main slide against rearward movement, and locking said sear means and firing member in firing position, and preventing effective actuation of the 105 firing member to fired position in the event of accidental movement thereof to fired position, means for moving said detaining and controlling means in direction reverse to the 110 first mentioned direction when the firing 115

member is moved to fired position, a grip-compressible member engageable with said detaining and controlling means when in position of safety to block said detaining and controlling means in said locking position, and releasable from said engagement by grip-compression, and trigger means engageable with said sear means to move said sear means, when said grip-compressible member is grip-compressed, for releasing said firing member for movement to fired position.

member in firing position, and preventing effective contact of the firing member with said firing-pin in the event of accidental movement of the firing member to fired position, means for moving said detaining and controlling means in direction reverse to the first-mentioned direction when said firing member is movable to fired position, a grip-compressible member engageable with said detaining and controlling means when in position of safety, to block said detaining and controlling means in said locking position, and releasable from said engagement by grip-compression, and trigger means engageable with said sear means to move said sear means, when said grip-compressible member is grip-compressed, for releasing said firing member for movement to fired position.

7. In a firearm, in combination, a frame 85
of said firearm, a main slide movable rear-
wardly and forwardly on said frame and
provided with a rear-face, a rigid breech-
block movable with said main slide and mov-
able rearwardly by powder gases and when 90
so moved transmitting rearward movement
to said main slide, and comprising a firing-
pin, a firing member movable to firing posi-
tion and to fired position and engageable
with said firing-pin, sear means engageable 95
with said firing member, means for moving
said firing member to fired position, slidable
detaining and controlling means engage-
able with said rear-face of the main slide,
means for moving said detaining and con-
trolling means in direction for locking said 100
main slide against rearward movement, and
locking said sear means and firing mem-
ber in firing position, and preventing ef-
fective contact of the firing member with 105
said firing-pin in the event of accidental
movement of the firing member to fired po-
sition, means for moving said detaining and
controlling means in direction reverse to the
first mentioned direction when said firing 110
member is moved to fired position, a grip-

operable member engageable with said detaining and controlling means when in position of safety, to block said detaining and controlling means in said locking position, 115 and releasable from said engagement by grip-compression, spring means for moving said firing member to fired position, and affording grip-compression of said grip-operable member, and for returning the grip-operable member to position of safety after grip-compression, and trigger means engageable with said sear means to move said sear means, when said grip-operable member is grip-compressed, for releasing said firing 120 member for movement to fired position. 125

8. In a firearm, in combination, a frame of said firearm, a main slide movable rearwardly and forwardly on said frame and provided with a rear-face, a rigid breech- 130

- block movable with said main slide and movable rearwardly by powder gases and when so moved transmitting rearward movement to said main slide, and comprising a firing-pin, a firing member movable to firing position and to fired position and engageable with said firing-pin, a sear member engageable with said firing member, a slidable detainer and controller engageable with said rear-face of the main slide, means for moving said detainer and controller upwardly for locking said main slide against rearward movement, and locking said sear member and firing member in firing position, and preventing effective contact of the firing member with said firing-pin in the event of accidental movement of the firing member to fired position, means for moving said detainer and controller downwardly when said firing member is moved to fired position, a grip-operable member engaging said frame and engageable with said detainer and controller when in position of safety to block said detainer and controller in said locking position, and releasable from said engagement with said detainer and controller by grip-compression, spring means for moving said firing member to fired position, and affording grip-compression of said grip-operable member, and for returning the grip-operable member to position of safety after grip-compression, and a trigger member engageable with said sear member to move said sear member, when said grip-operable member is grip-compressed, for releasing said firing member for movement to fired position.
9. In a firearm, in combination, a frame of said firearm comprising a grip-stock, a main slide movable rearwardly and forwardly on said frame provided with an actuation face and with a rear-face, a breechblock movable with said main slide and movable rearwardly by powder gases and when so moved transmitting rearward movement to said main slide, and engageable with said frame and with said actuation face, and comprising a firing-pin, a firing-hammer movable to firing position and to fired position and engageable with said firing-pin, and provided with a cock-notch and with an eccentric cam face, a sear member provided with a locking-shoulder for engaging said cock-notch and provided with a face for engaging said eccentric cam face, and provided with an arm, and with an end-face, and provided with a spring-actuated contactor for engaging said firing hammer, a slidable detainer and controller provided with a face for engaging said main slide, and provided with a shoulder having an upper face for engagement therewith of said arm of the sear member to move the slidable detainer and controller downwardly when said firing hammer is moved to fired position, and provided with means for receiving a trigger member, and provided with a bottom-side, and with an end-face, a spring operated actuator for engaging said end-face of the detainer and controller to move said slidable detainer and controller upwardly when said firing member is moved to firing position to lock said main slide, and lock said sear member and firing hammer in firing position, a hinged grip-safety member pivotally attached to said grip-stock at its lower end and engaging said frame at its upper end, and provided with a locking-prong for engaging said bottom-side of the slidable detainer and controller to block the detainer and controller in upward position when the grip-safety member is in position of safety, and releasable from said last mentioned engagement by grip-compression, a spring seated in said grip-safety member, a rod pivotally attached at its upper end to said firing hammer, means movable in said grip-safety member providing an abutment for said spring and a seat for the lower end of said rod, and a trigger member received in said slidable detainer and controller and provided with an end-face engageable with said end-face of the sear member by pull upon said trigger member when said grip-safety member is grip-compressed to move said sear member.
10. In a firearm, in combination, a frame of said firearm, a main slide movable rearwardly and forwardly on said frame, slidable detaining and controlling means engageable with said main slide, actuating means for said slidable detaining and controlling means, a firing member movable to firing position and to fired position, and sear means engageable with said firing member and engageable with said detaining and controlling means and provided with actuating-contacting means; said firing member, when moved to firing position, engaging said actuating-contacting means for moving said sear means to permit movement of said slidable detaining and controlling means by said actuating means to lock said main slide against rearward movement and lock said sear means and firing member in firing position; said sear means when said firing member is moved to fired position being moved by the firing member and engaging said slidable detaining and controlling means to move the slidable detaining and controlling means to unlocking position.
11. In a firearm, in combination, a firing member movable to firing position and to fired position, slidable detaining and controlling means, actuating means for said slidable detaining and controlling means, and sear means engageable with said firing member and engageable with said detaining and controlling means and provided with

- 7
- actuating-contacting means, said firing member when moved to firing position, engaging said actuating-contacting means for moving said sear means to permit movement 5 of said slideable detaining and controlling means by said actuating means in direction to lock said sear means and firing member in firing position; said sear means when said firing member is moved to fired position 10 being moved by the firing member and engaging said slideable detaining and controlling means to move the slideable detaining and controlling means in direction reverse to the first mentioned direction.
- 15 12. In a firearm, in combination, a frame of said firearm, a main slide movable rearwardly and forwardly on said frame, a slideable detainer and controller engageable with said main slide, an actuator for moving said 20 slideable detainer and controller upwardly, a firing member movable to firing position and to fired position, a sear member engageable with said firing member, and engageable with said slideable detainer and controller, 25 and provided with an actuator-contactor; said firing member when moved to firing position engaging said actuator-contactor for moving said sear member to permit upward movement of said slideable detainer and controller by said actuator to lock said main slide against rearward movement and lock said sear member and firing member in firing position; said sear member when said firing member is moved to fired position 30 being moved by the firing member and engaging said slideable detainer and controller to move the slideable detainer and controller downwardly.
13. In a firearm, in combination, a firing 40 member movable to firing position and to fired position, a slideable detainer and controller, an actuator for moving said slideable detainer and controller upwardly, and a sear member engageable with said firing member, 45 and engageable with said slideable detainer and controller, and provided with an actuator-contactor; said firing member when moved to firing position engaging said actuator-contactor and moving said sear member to permit upward movement of said slideable detainer and controller by said actuator to lock said sear member and firing member in firing position; said sear member when said firing member is moved to 50 fired position being moved by the firing member and engaging said slideable detainer and controller to move the slideable detainer and controller downwardly.
14. In a firearm, in combination, a firing 60 member, slideable detaining and controlling means, sear means engageable with said firing member, and engageable with said slideable detaining and controlling means, trigger means, and actuating-contacting means 65 engaging said firing member to move said sear means to position for engagement by said trigger means.
15. In a firearm, in combination, a main slide, a firing member, slideable detaining and controlling means engageable with said main slide, sear means engageable with said firing member and engageable with said detaining and controlling means, trigger means, and actuating-contacting means engaging said firing member to move said sear 70 means to position for engagement by said trigger means.
16. In a firearm, in combination, a firing member, slideable detaining and controlling means, sear means engageable with said firing member, and engageable with said slideable detaining and controlling means, trigger means, and an actuator-contactor carried by said sear means and engaging said firing member to move said sear means to position 75 for engagement by said trigger means.
17. In a firearm, in combination, a main slide, a firing member, slideable detaining and controlling means engageable with said main slide, sear means engageable with said firing member, and engageable with said slideable detaining and controlling means, and an actuator-contactor carried by said sear means and engaging said firing member to move said sear means to position 80 for engagement by said trigger means.
18. In a firearm, in combination, a firing member movable to firing position and to fired position, trigger means, sear means engaging said firing member and engageable with said trigger means, the sear means not being engageable with said trigger means when the firing member is in fired position, and means co-operative between the sear means and firing member for moving the sear means for engagement by the trigger means when the firing member is moved to 85 fired position.
19. In a firearm, in combination, a firing member movable to firing position and to fired position, trigger means, sear means engaging said firing member and engageable with said trigger means, the sear means not being engageable with said trigger means when the firing member is in fired position, and means appurtenant to the sear means and engaging the firing member for moving the sear means for engagement by the trigger means when the firing member is moved to 90 fired position.
20. In a firearm, in combination, a firing member movable to firing position and to fired position, trigger means, sear means engaging said firing member and engageable with said trigger means, the sear means not being engageable with the trigger means when the firing member is in fired position, and actuating-contacting means carried by the sear means and engaging the firing member for moving the sear means for engagement by the trigger means.

ment by the trigger means when the firing member is moved to firing position.

21. In a firearm, in combination, an operatively arranged and connected firing-pin, 5 a firing member for actuating the firing pin and movable to firing position and to fired position, means for actuating the firing member to fired position, trigger means, sear means engaging said firing member and engageable with said trigger means, the sear means not being engageable with the trigger means when the firing member is in fired position, and means coöoperative between the sear means and firing member for moving 10 the sear means for engagement by the trigger means when the firing member is moved to firing position.

22. In a firearm, in combination, a firing member movable to firing position and to 20 fired position, trigger means, sear means engaging said firing member and engageable with said trigger means, the sear means not being engageable with the trigger means when the firing member is in fired position, 25 slideable detaining and controlling means for locking said sear means and firing member in firing position and movable to unlocking position, means for retaining said detaining and controlling means in said locking position and for releasing the same, and means 30 coöoperative between the sear means and firing member for moving the sear means for engagement by the trigger means when the

firing member is moved to firing position, said detaining and controlling means, when 35 released by said retaining means, being moved to unlocking position when the firing member is moved to fired position.

23. In a firearm, in combination, a frame of said firearm, a slide movable rearwardly 40 and forwardly on said frame, a firing member movable to firing position and to fired position, trigger means, sear means engaging said firing member and engageable with said trigger means, the sear means not being 45 engageable with the trigger means when the firing member is in fired position, slideable detaining and controlling means for locking said slide when the firing member is in firing position and for locking said sear means 50 and firing member in firing position, means for retaining said detaining and controlling means in said locking position and for releasing the same, and means coöoperative between the sear means and firing member for 55 moving the sear means for engagement by the trigger means when the firing member is moved to firing position, said detaining and controlling means, when released by said retaining means, being moved to unlocking position by the sear means when the firing member is moved to fired position.

JOHN D. PEDERSEN.
